(57) **CLAIM**

The ornamental design for a valve container, as shown and described.

DESCRIPTION

FIG. 1 is a front elevation view of a valve container, showing my new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a cross-sectional view along lines 1-1 of FIG. 1;

FIG. 8 is a cross-sectional view along lines 2-2 of FIG. 3;

FIG. 9 is a front elevation view thereof shown separately to show aspects of the design that are not visible when combined.

FIG. 10 is a rear elevation view thereof;

FIG. 11 is a right side elevation view thereof;

FIG. 12 is a left side elevation view thereof;

FIG. 13 is a top plan view thereof; and,

FIG. 14 is a bottom plan view thereof.

The broken lines in the drawings depict portions of the valve container that form no part of the claimed design.
